CHIME SIGNAL

John G. Jolly, Cincinnati, Ohio, assignor to Nu Tone,
Inc., Cincinnati, Ohio, a corporation of New York

Application November 20, 1956, Serial No. 43,845

Term of patent 14 years

(Cl. D72—1)

Figure 1 is a perspective view of a chime signal, showing my new design.

Figure 2 is an enlarged fragmentary front elevational view of the upper portions of the signal in Figure 1 with the resonators shown broken away for convenience of illustration.

Figure 3 is a vertical sectional view taken substantially through the center of Figure 2; and

Figure 4 is a cross-sectional view taken through the lower areas of the signal shown in Figure 2.

The top of the chime signal and the other side not shown are substantially plain.

I claim:

The ornamental design for a chime signal, substantially as shown and described.
